Patented June 13, 1922.

2 SHEETS—SHEET 2

UNITED STATES PATENT OFFICE.

MILES D. JOYNER, OF SPARTANBURG, SOUTH CAROLINA.

CROSSHEAD.

1,419,457.

Specification of Letters Patent. Patented June 13, 1922.

Application filed June 1, 1921. Serial No. 474,086.

To all whom it may concern:

Be it known that I, MILES D. JOYNER, a citizen of the United States, residing at Spartanburg, in the county of Spartanburg 5 and State of South Carolina, have invented new and useful Improvements in Cross-heads, of which the following is a specification.

This invention has reference to cross heads 10 of any form to which it may be adapted and it relates more particularly to an adjustable gib and parts associated therewith, whereby to provide for take up of wear and to insure smooth running and long life of the machinery in which the cross head is installed.

In accordance with the invention, the cross head comprises a body or boxing composed of side plates connected together at one end of the cross head by the piston rod 20 socket and at the other end of the cross head by the pivot bolt of the corresponding pitman bearing.

The side plates, which may have parallel top and bottom edges, engage top and bottom 25 gibs and between the side plates and gibs are connected wedge strips, one wedge strip, which is of U-form, being interposed between the upper edges of the side plates and the uppermost gibs, and the other wedge 30 strip being composed of the side plates and the lowermost gibs.

Between the upper pair of gibs and also between the lower pair of gibs is a taper key for spreading the gibs of each pair apart 35 and provision is made for connecting the taper key to the U-shaped wedge member associated with it, in order to draw the parts up tight.

The side plates near their top and bottom 40 edges are traversed by bolts connecting them together, and these bolts where traversing the side plates are tapered longitudinally, so that they may snugly fit the parts they traverse.

The gibs where traversed by the bolts are 45 of web and flange formation, while the bodies of the gibs are made heavy to provide ample bearing against the parallel slide bars along which the cross head 50 travels.

The invention also contemplates additional means for compensating for wear as will hereinafter appear, and provision is made for taking up the wear both laterally 55 and longitudinally of the cross head so that the gibs may be adjusted from time to time

and the cross head will run smoothly without play, thus greatly prolonging the life of the cross head and particularly of the gibs and contributing to smooth, noiseless 60 action.

The invention will be best understood from a consideration of the following detailed description taken in connection with the accompanying drawings forming part of this 65 specification, with the understanding, however, that the invention is not confined to any strict conformity with the showing in the drawings, but may be changed and modified so long as such changes and modifications mark no material departure from the salient features of the invention as expressed in the appended claims.

In the drawings:

Fig. 1 is a side elevation of a cross head 75 embodying the invention.

Fig. 2 is a longitudinal vertical section thereof.

Fig. 3 is a cross section in the plane of the pitman pivot bolt.

Fig. 4 is a longitudinal section on the line 4—4 of Fig. 2.

Fig. 5 is a perspective view of one of the gibs.

Fig. 6 is a perspective view of a taper 85 key.

Fig. 7 is a perspective view of a double wedge used in conjunction with the side plates and gibs.

Fig. 8 is an elevation of a key through 90 which the side plate bolts extend.

Fig. 9 is an elevation of a modified form of structure used to adapt old cross heads to eccentric bolts without employing the twin wedge.

Fig. 10 is a section on the line 10—10 of Fig. 9.

Fig. 11 is a face view of one of the perforated washers employed in the structure of Figs. 9 and 10.

Fig. 12 is a fragmentary section similar to Fig. 3 but showing a modification thereof.

Fig. 13 is a section through an eccentric bushing for adjusting the gib.

Referring to the drawings, there is shown 105 in Figs. 1 and 2 a cross head A, to one end of which there is secured a piston rod B by means of a socket 1 and the rod is made fast to the socket 1 by a wedge 2. The socket 1 is or may be in one piece with side plates 3 110 between which the socket 2 is cast. Traversing the side plates 3, near their other ends,

- is a pivot bolt 4, passing through a brass 5 in the corresponding end of a pitman 6, which may be assumed as extending to the part to be driven through the cross head.
- 5 The body of the cross head is formed in part by the two side plates 3, which may be made flat and sufficiently heavy for the purpose. The pivot bolt 4 is formed with a taper head 7 having a seat 8 in the corresponding side plate 3 and a taper shank 9 in the same side plate. The body of the bolt extends from the taper seat 9 to the other side plate where it is provided with a taper shank 10 passing through a taper seat 11 in the second side plate and beyond the second side plate the bolt 4 has a threaded continuation 12 to which is applied a nut 13 held in place by a cotter pin 14 or other suitable means.
- 10 Fast to the plates 3 and extending between the plates at the upper and lower edges thereof, are pairs of gibs 15, each composed of a block-like body member 16 overhanging the plates 3 at the ends and along one edge having a longitudinal taper seat 17 from the inner side of which a flange 18 projects opposite to the body 16. Perpendicular to the flange 18 on the side thereof remote from the seat 17 is a series of ears 19 of progressively different lengths, the ears of one gib being opposite to the ears of the companion gib, so as to leave a space between them with the spaces in line diagonal to the length of the cross head, as best shown in Fig. 4. The flange 18 between the ears 19 has perforations 20, traversed by bolts 21, which bolts also traverse the edge portion of the side plates 3.
- 15 One end of each bolt 21 is formed into a head 22, adjacent to which the bolt has a taper shank 23. The end of each bolt 21 remote from the taper portion 23 and where it passes through the opposite side plate 3 and perforation 20 in the opposite gib is tapered, as indicated at 24 and beyond the portion 24 has a screw-threaded continuation 25 terminating in a squared end 26. Applied to the threaded portion 25 are lock nuts 27. The mid portion of the bolt 21 is eccentric to the longitudinal axis of the bolt, so that when the bolt is turned, there is a respective movement between the parts traversed by the bolt due to the eccentricity of the mid portion of the bolt, so that the various portions are adjusted by the turning of the bolt with respect to the parts engaged thereby.
- 20 Introduced between the taper seats 17 of the opposite gibs 16 and the like edges of the side plates 3 are matching legs 28 of U-shaped wedges 29, the legs being joined at the thicker ends by a yoke 30 having a perforation 31 midway between the two legs. There is also provided a key 32, shown separately in Fig. 6 and in plan view in Fig.
- 25 4, and appearing in cross section in Fig. 3, this key conforming more or less to the longitudinal shape of the gib and having along one edge a widened portion 33 in which is produced a longitudinal slot 34. At one end 70 of the widened portion 33, there is formed an eye 35 perpendicular to one face of the key. The key is introduced between opposite gibs and engaged by the ears 19 between which it is lodged and the perforations 20 75 are arranged on opposite sides of the slot 34, so that the bolts 21 when traversing the perforations 20 also traverse the slot 34.
- 30 Encircling one of the bolts, say that bolt nearest to the yoke 30 of the double wedge 80 29, is the eye 36 of an eye bolt 37, the shank of which eye bolt passes through the ear 35 and through the perforation 31 of the yoke 30 and has then applied to it lock nuts 38. On the side of the ear 35 remote from the 85 yoke 30, the eye bolt 37 has another nut 39 applied thereto, so that the double wedge 29 may be drawn up tight and forced between the ears 19 of the gibs and locked in the adjusted position. At the same time, the 90 key 32, which is in the form of a plate having a slight longitudinal taper toward the ear 35, bears upon the adjacent ends of the ears 19, thereby tending to force the gibs apart until separation of the gibs is prevented by the engagement of the side plates with the heads 23 of the bolts 21 and with the nuts 27 at the opposite ends of the bolts 21. Further adjustment is provided for by the employment of shims 40 between the 100 inner faces of the top and bottom portions of the side plates and the outer faces of the flanges 18.
- 35 The gibs of each pair have matching rabbits 41 to receive top and bottom parallel 105 guide bars 42 permitting the cross head to reciprocate under the impulses of the piston rod B and thereby impart motion to the pitman 6 in the usual manner.
- 40 When the cross head is assembled, all 110 looseness is taken up by adjusting the bolts 21 to spread the gibs so that they embrace the guide bars 42 and are moved one away from the other causing a neat fit between the bars 42 and the rabbits 41. At the same time, the 115 double wedges 29 take up any looseness between the side plates 3 and the gibs in conjunction with the shims 40. Moreover, the taper form of the wrist pin 4, where passing through the side plates 3, provides for 120 taking up any looseness which might otherwise occur or be due to wear between the pitman 6 and the cross head.
- 45 After the cross head has been in use for a while, wear occurs and then it is necessary 125 to readjust the several parts, which adjustment is facilitated by the adjustments for which provision is made and such adjustments can be performed with great facility.
- 50 In order to adapt the invention to a cross 130

head in which eccentric bolts are used in the absence of the twin or double wedge, the structure shown in Figs. 9 to 11 may be employed. In such case, eccentric bolts 21^a, 5 one of which is shown in Fig. 10 may be used. Each bolt 21^a between the taper portion 24 and the threaded extension 25 is provided with a squared portion 43 to receive a washer 44 bearing against the outer 10 face of the respective side plate 3 and the washer 44 has a central passage 45 of square contour or of any other non-circular contour corresponding to the non-circular portion 43 of the bolt. Each washer 44 is provided 15 with a circular series of perforations 46 to receive a pin 47 extending through a perforation 46 in the washer and made fast in the neighboring side plate 3. In this way, the bolt 21^a may be held in the adjusted position 20 to which it is moved in order to take up wear between the gibs and the guide bars 42, with the lock nuts 27 serving to relieve the pins 46 from excessive strains and also the pin 47 will prevent loosening of the bolt 25 21^a due to slipping with respect to the lock nuts.

The shims 40, as shown separately in Fig. 8, are made with slots 48 to facilitate their application to the bolts 21 or 21^a.

30 Instead of taking up side lateral play with shims, as indicated in Fig. 3, the arrangement shown in Fig. 12 may be employed and is the preferable form. The gibs 16 in the showing of Fig. 12 have each a beveled undercut face 16^a and the side plates 3 are similarly undercut and beveled, as shown at 3^a, so that when the key 32 and the bolts 21 are adjusted, both the up and down and the side play are taken up simultaneously.

40 Instead of using bolts 21 with eccentric mid-portions, the arrangement shown in Fig. 13 may be employed. The mid portion 21^a is made square in cross-section and in line with the longitudinal axis of the bolt, 45 and on the square portion there is applied a cylindrical bushing 22^a with a square passage therethrough eccentric to the longitudinal axis thereof so that the bushing is eccentric and turns with the bolt. The arrangement of Fig. 13 provides a cam-bolt structure which may be used in some forms of cross-heads without the necessity of re-drilling them larger.

What is claimed is:—

55 1. In a cross head, a two part gib with matching rabbets to receive a guide bar on which the gib travels, said parts of the gib having a longitudinal flange on the edge remote from the rabbet with the flange provided with ears projecting toward the other part of the gib and of progressively different lengths from one end of the gib to the other with the ears defining a channel running diagonally of the gib, and a longitudinally 60 tapered key lodged between the adjacent 65

ends of the ears and shaped to spread the two parts of the gib by longitudinal movement of the key.

2. In a cross head, a two part gib with matching rabbets to receive a guide bar on 70 which the gib travels, said parts of the gib having a longitudinal flange on the edge remote from the rabbet with the flange provided with ears projecting toward the other part of the gib and of progressively different 75 lengths from one end of the gib to the other with the ears defining a channel running diagonally of the gib, and a longitudinally tapered key lodged between the adjacent 80 ends of the ears and shaped to spread the two parts of the gib by longitudinal movement of the key, the two parts of the gib being provided with bolts connecting them together, the key having an ear formed thereon, and an eye-bolt connected to relatively 85 fixed parts of the structure and traversing the eye bolts of the key to cause movement of the latter lengthwise of the cross head.

3. In a cross head, an elongated gib structure having one edge provided with a rabbet 90 to receive a guide bar along which the cross head travels and the opposite edge formed with an inset longitudinal flange having laterally extended ears projecting therefrom with the ears of progressively different 95 lengths from one end of the gib toward the other, and the gibs being arranged in pairs with the ears matching and separated to form a channel between them.

4. In a cross head, an elongated gib structure comprising two parts, each having one edge provided with a rabbet to receive a guide bar along which the cross head travels and the opposite edge formed with an inset longitudinal flange having laterally extended 100 ears projecting therefrom with the ears of progressively different lengths from one end of the gib toward the other, and the gibs being arranged in pairs with the ears matching and separated to form a channel between 105 them.

5. A cross head comprising opposed face plates, longitudinally divided gibs each with longitudinal flanges on one edge entering between the face plates and the flanges provided with laterally extended ears of progressively different lengths from one end of the gib toward the other and separated at their adjacent ends to form a longitudinally 110 tapered channel, a key adapted to the taper 115 channel and correspondingly tapered in the direction of its length, and bolts passed through the face plates and the intervening flanges of the gibs and also through the key with the latter having a longitudinal slot to 120 accommodate the bolts, said bolts having eccentric bearings in the gib flanges to project or retract the gibs, and the key having means of moving it longitudinally to vary 125 the spread of the divided gib. 130

6. A cross head comprising separated side plates, a socket connecting the side plates at one end to receive one end of a piston rod, a pivot bolt connecting the side plates near the other end to receive one end of a pitman, two part gibs between the top and bottom edges of the side plates with the division between the two parts of the gibs running diagonally of the cross head, a taper key, lodged between and separating the two parts of the gibs, and rotatable bolts extending through the side plates and the gibs with the bolts eccentrically mounted to form cams for adjusting the gibs with relation to the cross heads.
7. A cross head comprising separated side plates, a socket connecting the side plates at one end to receive one end of a piston rod, a pivot bolt connecting the side plates near the other end to receive one end of a pitman, two part gibs between the top and bottom edges of the side plates with the division between the two parts of the gibs running diagonally of the cross head, a taper key, lodged between and separating the two parts of the gibs, and rotatable bolts extending through the side plates and the gibs with the bolts eccentrically mounted to form cams for adjusting the gibs with relation to the cross heads, each bolt having a head at one end with a taper shank and at the other end also provided with a taper shank with the intermediate portion of the bolt eccentric to the longitudinal axis thereof and having the taper portion mounted in taper seats in the side plates and the eccentric portion extending through the gibs whereby to cause the projection and retraction of the gibs in accordance with the direction of turning of the bolts.
8. A cross head comprising separated side plates, a socket connecting the side plates at one end to receive one end of a piston rod, a pivot bolt connecting the side plates near the other end to receive one end of a pitman, two part gibs between the top and bottom edges of the side plates with the division between the two parts of the gibs running diagonally of the cross head, a taper key, lodged between and separating the two parts of the gibs, and rotatable bolts extending through the side plates and the gibs with the bolts eccentrically mounted to form cams for adjusting the gibs with relation to the cross heads, each bolt having a head at one end with a taper shank and at the other end also provided with a taper shank with the intermediate portion of the bolt eccentric to the longitudinal axis thereof and having the taper portion mounted in taper seats in the

side plates and the eccentric portion extending through the gibs whereby to cause the projection and retraction of the gibs in accordance with the direction of turning of the bolts, each bolt having a threaded extension at the end remote from the head, and a non-circular terminal at the same end as the threaded extension.

9. A cross head comprising side plates separated and connected together, two part gibs carried by the side plates and lodged between and extending from the top and bottom edges of the side plates, and double wedge devices between the top and bottom edges of the side plates and the gibs whereby to expand the gibs from and permit their retraction toward the central portion of the cross head, and a taper key lodged between the two parts of each gib and movable lengthwise to cause the lateral spread or retraction of each two part gib to adjust the width of the gib to compensate for wear.

10. A cross head comprising connected side plates for joining a piston rod to a pitman, two part gibs entering between like edges of the side plates and projecting beyond said like edges and there provided with matching rabbets to receive the cross head guide bars, said two part gibs having a division between them running diagonally of the gib, a double wedge between each two part gib and the corresponding edges of the side plates, with the double wedge joined by a yoke, a taper key with a longitudinal slot therein and having at one end an offset ear with the ear and yoke of the double wedge having matching perforations, eccentric bolts extending through the top and bottom edges of the side plates, the slots in the keys and the two part gibs with the bolts seated to adjust the gibs toward and from the guide bars for the cross head, and a connection between one of the bolts and the ear on each key and the yoke on each double wedge, whereby to adjust the parts of the cross head to eliminate all lost motion due to wear.

11. In a cross head, a two part gib with beveled undercuts, side plates similarly undercut and engaging the undercut portions of the gibs, a taper key between the two parts of the gib; and cam bolts traversing the side plates and gibs to cause the taking up of wear both laterally and in a direction perpendicular thereto.

In testimony, that I claim the foregoing as my own, I have hereto affixed my signature.

MILES D. JOYNER.
